UNITED STATES PATENT OFFICE

2,506,072

COUNTING AND PRINTING MECHANISM

Laura Blanchette Duncan, Miami, Fla.

Application December 31, 1946, Serial No. 719,392

4 Claims. (Cl. 346—98)

1

This invention relates to a printing counter or counting and printing mechanism, and more particularly to such mechanism adapted for general use such as to be utilized in diaper laundries or otherwise, for counting diapers or other articles which are contained in a batch, and especially articles of the same kind, so as to assist in the counting, printing and pricing of the laundry on laundry slips and for totalizing a day's business, or for other known periods.

The primary object of this improvement is to record in detail the mechanism and arrangements of the printing counter encased as shown in Figure 1, and which forms part of the whole of the diaper counting machine, so that it may be marketed aside and apart as a self entity for any other purpose whatsoever.

The invention is an improvement upon the device shown in my prior application Serial No. 620,299 filed October 4, 1945, and relates more particularly to an electric eye mechanism, by which the diapers or other articles are counted as they are distributed into trucks or other containers for further processing.

Another object of the present improvement, is to eliminate the necessity of employing a hopper and baffle plate at the end of the conveyor, by which the articles are counted by checking the travel thereof and causing them to drop to a point beneath the truck or receptacle to intercept the light rays of the electric eye cast upon a photosensitive cell, to actuate an electrically operated counting mechanism or counter, by which the number of articles is totalized and ascertained.

The invention further consists in so mounting the electric eye that the light rays therefrom impinging upon the photosensitive cell, is positioned within the length of the conveyor so as to be intercepted by the articles as they are carried up the conveyor after being sorted and distributed upon the conveyor, for discharging the same into the trucks or receptacles because natural gravitation of the articles falling at the end of conveyor was too slow and had a tendency to permit several articles to bog together when speed of conveyor was heightened or increased.

It is therefore an important object of the invention, to provide a novel arrangement of electric eye upon the conveyor for conveying the

2

soiled diapers or the like to the trucks and means associated therewith and actuated thereby, whereby the diapers or other articles being conveyed for distribution to the trucks may be counted.

Another object of the invention is to provide a portable diaper counting mechanism which may be readily moved about from place to place where it is desired to use the same, and upon which the diapers or other articles may be placed from a sorting table, by an operator and counted as they are conveyed to the trucks, the electric eye mechanism serving to interrupt the ray of light which is played upon the photosensitive cell, so that an electromagnet is intermittently energized and de-energized to actuate the counter for giving the total number of articles conveyed and distributed to the trucks.

A still further object of the invention, is to provide novel driving connections by which the counter is actuated, by the electrical pulsations or interruptions to the flow of current caused by the diapers or other articles passing the electric eye mechanism during the conveyance thereof, and for resetting the counter back to zero, so that each batch of articles may be separately counted to facilitate checking of the number of articles and the making out of the laundry slips as well as in counting for the cost thereof or charges to be made for the laundering of the different batches, and the total business transacted during a day or other definite periods.

Another and still further object of the invention, is to provide an electrically actuated counter mechanism having novel drive means as well as novel resetting means, and in which an ink take is provided for number wheels by which the recording of the number of articles may be stamped on cards or slips therefrom, and in which the entire mechanism is visible at all times during the operation thereof.

Another object of the invention is to provide a device which is extremely compact, and adapted to be mounted upon a wheeled frame supporting a tiltable conveyor belt, the angle of inclination of which may be readily adjusted or varied as desired.

Other objects and advantages reside in the details of construction and operation as more fully hereinafter described and claimed, reference be-

ing had to the accompanying drawings forming part hereof, wherein like numerals refer to like parts throughout, and in which:

Figure 1 is a perspective view showing a glass enclosure for the counting and stamping device and mechanism, with the operating handle and card insertion slot.

Figure 2 is a horizontal sectional view of the case, with the mechanism in elevation, taken on the line 2—2 of Figure 1.

Figure 3 is a transverse vertical sectional view of the case with the mechanism in elevation, taken on the line 3—3 of Figure 2.

Figure 4 is a side elevation of the complete conveyor mechanism showing the location of the electric eye and counting and stamping device.

Figure 5 is a longitudinal section of the case, with the mechanism in elevation, taken on the line 5—5 of Figure 3.

Figure 6 is a longitudinal section of the stamping hammer, guide and card slot, with the counting device in elevation, taken on the line 6—6 of Figure 3.

Figure 7 is a transverse section of the stamping hammer, ribbon guide, card slot and counting device, taken on the line 7—7 of Figure 2 and

Figure 8 is a fragmentary plan view of the conveyor, showing the relation of the electric eye and photosensitive cell of the counting and stamping device operating mechanism.

Referring to the drawings in detail, in which like reference characters designate corresponding parts throughout the several views, and referring more particularly to Figures 4 and 8 of the drawings, there is generally indicated at 10, a supporting base or platform of a portable type, preferably wheeled, carried on casters or rollers 11, preferably swiveled to turn in order to guide the device about the floor of a laundry or wherever used. The wheeled base or platform is provided with spaced side uprights 12 reinforced as by angle supporting members or braces 13 and terminating in journal brackets or bearings 14. Brackets 14 carry the extremities of a pivot shaft or axle 15 in the bearings thereof, which pivotally support a frame generally indicated at 16, adapted to carry a conveyor belt mechanism generally indicated at 17.

The frame 16 of the conveyor includes two spaced parallel aligned supporting members 18, provided at their extremities with aligned journals 19 and 20 respectively, which journals carry axles 21 and 22, respectively, which in turn support rollers 23 and 24 respectively. An endless conveyor belt 25 extends about the rollers 23 and 24, supporting guide rollers 26 being provided at suitable spaced intervals under the upper portion of the conveyor belt and journaled in the side walls of the frame, if desired to support the upper lap of the endless conveyor belt movably thereon. The conveyor belt is adapted to be driven in any suitable manner, as shown and described in my prior application above referred to, by means of a motor driven pulley and belt, or otherwise so as to continuously move the upper lap of the belt in an upward direction upon the inclined endless conveyor and frame thereof as described.

Side plates 27 may be provided at opposite sides of the conveyor frame 16, against which the soiled diapers or other articles to be laundered and counted in the process of conveying the same to the wheeled trucks or receptacles at the upper discharge end of the conveyor, may be thrown

and guided although only one of such plates is ordinarily necessary as shown, at the far side of the conveyor, against which the articles may strike when picked up by the operator from a distributing table, and placed or thrown upon the conveyor, to insure the same being carried upwardly through the discharge end of the conveyor for deposit into the receptacles of the wheeled trucks or otherwise.

Means may be provided for varying the angular adjustment of frame 16, and hence its associated conveyor belt, and such means may take the form of tubular standards 28 pivotally secured as at 29, to suitable bearing brackets attached to the base 10 at the front end thereof and within which are slidably mounted rods 30 capable of vertical adjustment by means of a series of holes 32 in each rod adapted for engagement by a pin 31, and pivoted to hangers or bracket arms 33 secured to the sides of the frame 16. That is, each member 30 is provided with a plurality of apertures therein and is slidable within the member 28 of tubular form as shown and described, so as to secure the necessary adjustment by means of the pin 31 which is passed through suitable apertures in the tubular member 28 and adapted to engage in a selected one of the apertures 32 in the member 30, to hold the conveyor mechanism in any desired angular position or angle of inclination with its discharge end uppermost and its feed end lowermost where the plates or plate 27 is provided. Usually, a distributing table is placed adjacent the feed end of the conveyor, to receive the diapers or other articles which are picked up by the operator and deposited onto the conveyor or merely thrown against the plate or shield 27, to drop onto the conveyor to be carried upwardly to be counted and to actuate the counting mechanism as they pass the light rays of the electric eye mechanism and intercept the impingement of the light ray from the light source, onto the photoelectric or photosensitive cell at the opposite side thereof. This arrangement will be more fully described herein-after, and it is also noted that a hopper and baffle board or plate at the discharge end of the conveyor, provided in the prior construction, is entirely omitted in the present device, and the discharge end of the conveyor left freely open and unobstructed so that the articles may be discharged therefrom and fed into the usual wheeled laundry trucks or the like, without striking an obstruction and necessitating that the laundry drop down through the hopper or chute at the end of the conveyor, thus maintaining a better sanitary condition and better distribution of the diapers or other articles to the laundry truck. Instead, as shown in Figures 4 and 8 of the drawings, an electric eye mechanism is provided consisting of a light source 34 on one side of the conveyor frame 16, and a light sensitive cell or photoelectric cell 35 on the other side thereof, so that the light ray or beam cast across the frame and conveyor from the light source 34 to the photoelectric or light sensitive cell 35, will strike the latter and maintain a certain resistance or operative position of the electrical circuit and mechanism mounted thereby, but will be intermittently and successively interrupted by the articles passing the light source and cell, causing interruptions of the light rays or beam, or breaking thereof, so that the photosensitive or photoelectrical cell, will be caused to intermittently energize and de-energize a magnet or other electrical mechanism in the circuit for operating a counting

and printing mechanism to be hereinafter more fully described.

The photosensitive cell 35, constitutes a photo switch which is connected to the light source 34 as shown in Figures 3 and 4 of the drawings by conductors 39 and 37 and the light beam is indicated at B. The photosensitive cell or switch 35 is in turn connected by conductors 38 and 39 to a relay or relay switch 40, one contact of which is connected to the conductor 36 as at 41 through a conductor 42 which is in turn connected to one side of a battery or other source of electrical energy 43, while the other side of said battery or source is connected by a conductor 44 with the conductor 37. The other contact of the relay switch is connected by a conductor 45 to one terminal 46 of a solenoid 47, and said other side of battery or source 43 is connected by a conductor 48 to the other terminal 49 of said electromagnet or solenoid housed within a counting and stamping device generally indicated at 50. A cable 51 containing the conductors 45 and 48 leads to the relay 40, from which a cable 52 containing the conductors 36 and 37 leads to the light source 34. An extension cord or cable 53 containing the conductors 41 and 42, 44, leads from the relay 40 and is provided with a plug 54 for connecting to the source of current or the battery 43, as by plugging it into a wall socket of the wiring of a building.

The counting and stamping device 50 is mounted upon a suitable shelf 55 supported by braces 56' on the uprights 12 and it includes a base 57' on which is mounted a casing 58' of glass or other transparent material reinforced at the edges or corners by metal bands or a frame 59', and having through its front panel a horizontal card insertion slot 60' and a vertical slot 62 in which is vertically movable an operating handle 61' as shown more particularly in Figure 1 of the drawings.

For the most part, the counting device may be of conventional construction modified in a manner to be hereinafter described, in reference to the novel actuating means and resetting mechanism constituting a part of the present invention, so that when the counter has been operated by the articles intercepting the light beam B between the light source 34 and the photoelectric cell or switch 35 in being carried upwardly for discharge into the wheeled truck by the conveyor 11, the relay will be intermittently actuated to successively make and break or intermittently interrupt the circuit to the electromagnet or solenoid 47 for actuating the counting and stamping device. The counting device proper has a plurality of number wheels 55 geared together or operatively connected with the usual decimal arrangement, in units, tens, hundreds, thousands, etc., each bearing characters from 1 to 9 and zero and being in the form of disks as shown mounted upon a shaft 56 from one end of which the usual reset knob is removed and substituted by a pinion 57 engaging rack 58 slideable in a guide 59 mounted at one end of the counter, transversely beneath the resetting shaft 56 of the counter. The counting device may be of conventional construction, such as the Veeder or Veeder-Root counter, except for the replacement of the resetting knob by the pinion 57 and has the usual number wheels 55 which are operated by the solenoid 47 and given a step by step motion by reason of the fact that articles passing before the electric eye cause the relay 40 to intermittently energize and de-energize the solenoid or electromagnet 47. A conventional typewriter ribbon 61 is fed from the

spools 62 and 63, the shafts 64 of which are journaled in bearings 65 carried at opposite ends of an angle iron frame member 66 extending transversely of the case and supported on the base 57' by a bracket 67 secured to the base and the angle iron 66. The ribbon 61 passes over the number wheels 55 and over smaller guide and tension spools 68 in line with the bottom of the slot 60' and maintained thereby flush with a lower guide plate 69 flared outwardly at the slot 60' and extending over the number wheels, at which point it is provided with a slot 70 for the ribbon 61 of the inked type similar to that used in a typewriter. The angle iron 66 also supports a top plate 71 above the plate 69, in line with the slot 60', forming a guide slot for the insertion of a card on which the number of articles of a batch to be washed, in a particular laundry order, is adapted to be stamped. The upper guide plate 71 is spaced from the lower guide plate 69, and is provided with a slot 72 above the slot 70, ribbon 61 and number wheels 55 of the counter, and is anchored on a strip or block 73 bolted or otherwise secured to the angle iron member 66.

Positioned on the upper guide plate 71 is a stamping hammer guide 74 slotted vertically at the front and back, as indicated at 75 to permit vertical movement therein, of the member 76 of the operating lever which has the stamping hammer or plunger 77 pivotally and slidably connected thereto as at 78 in a slot 79 to compensate for various angular relations between the hammer and the lever which is provided with the operating handle 61' extending through the slot 62 of the case for manually depressing the same by hand. The lever member 76 is pivotally mounted at its lower inner end portion, as indicated at 80 on an upright bracket or post 81 so as to permit operation of the hammer or plunger in the stamping hammer guide which is held normally upwardly under tension of a spring 82 operatively connected to the rearwardly projecting end of the lever member 76. The spring 82 is used in association with a dash pot, or conventional snuffer or hydraulic check 82', it being understood that the lever member 76 is free to move down in the stamping action against the tension of the spring but checked in its return movement to cushion the action and avoid jarring the counter wheels out of alignment. As will be noted, the ribbon 61 through which the numbers of the number wheels are printed on the card, passes over the number wheels flush with the guide plate 69 and is intermittently fed step by step, through the medium of a feed shaft 83 journaled in bearings 84 on the angle plate 66, through the medium of a ratchet disk 85 fixed to the feed shaft 83 and engaged by the ratchet head 86, said ratchet disk and ratchet head being held between collars 87 on shaft 83, and the ratchet head being pivoted at its hub on said shaft and having a lever or arm 88 pivoted at 89 to a link 90 in turn pivotally connected at its upper end to a transverse pin 91 carried by the operating lever between its pivot 89 and the stamping hammer 77 and operable by the hand lever 61'. The shafts 64 carry bevel gears 92 adapted to be selectively meshed with the bevel gears 93 having their hubs splined or keyed on the shaft 83 for feeding the inking ribbon 61 over the number wheels operated by the solenoid 47 in a step by step motion by the articles passing before the electric eye. By reason of

the ratchet means and gears as shown and described, the ribbon is fed from one spool to the other and intermittently advanced step by step by the ratchet means operating the feed shaft 83 to simultaneously operate the ribbon spools. The feed shaft 83 may be slidably mounted, with one end thereof projecting outwardly of the case and provided with a finger knob 94, whereby either one of the gears 93 may be placed in mesh with one of the gears 92 for the purpose of reversing the direction of the feed of the ribbon, although the shaft 83 is preferably stationary and the gears 93 shiftable by having their hubs or sleeves 95 engaged by forks 96 extending upwardly from a shiftable rod 97 positioned horizontally beneath and parallel to the shaft 83 in bearings 98 so that the spools may be reversed by shifting the rod 97 beneath the shaft 83, sliding one gear into mesh and the other out through the medium of the operating knob or button 94 positioned outside of the case 50. The small guide spools or rollers 68 are mounted on shafts 99 carried by bearing brackets 100 supported on the angle plate 66 and are idlers between which the stretch of inked ribbon 61 is horizontally positioned to pass through guides 101. These guides are positioned on opposite sides of the counter 60 above the bottom guide plate 69 and on each side of the slotted guide 74.

The pivot pin 91 projects laterally of the other side of the lever 76 and pivotally carries a depending curved arm 102 pivotally connecting at its lower end at 103 to the short arm of a bell crank lever 104 pivoted at 105 on a bracket 106 supported on the base 57, the arm or link 102 being curved rearwardly as shown. The other or longer arm of the bell crank lever 104 is pivotally connected at 107 to a rod or link 108 in turn pivotally connected at 109 to the rear end of the rack 58. As the operating lever is depressed, the ribbon will be fed by turning the shaft 83 driving the spools 62 and 63 through the gear drives by means of the ratchet mechanisms 85 and 86. The counter is intermittently operated by interrupting the light beam from the light source 34 to the photoelectric cell and switch 35 and through the relay 40, to close and open the circuit to the solenoid or electromagnet 47 to advance the numbers of the number wheels to give a total of the number of articles or diapers in a batch of laundry automatically, as the articles are carried up the conveyor for discharge into the wheeled trucks or baskets. Then, by inserting a card in the slot 60', and operating the handle 61' of the lever 76, the stamping mechanism is operated by lowering the hammer or plunger 77 in the stamping hammer guide 74 to press the card against the ribbon 61 and the digits on the numbering wheels 55, to print the number of articles thereon as thus totalized. Since the rack 58 is advanced each time the pinion 57 is turned with the numbering wheels, upon downward movement of the operating lever, the rack 58 will be shifted in the opposite direction to reverse the rotation of the pinion and the numbering wheels, for resetting the counter upon the upward movement of the operating lever after printing the total number of articles on the card. An adjustable stop lug in the form of a screw 110 threaded through a bracket 111 on the bracket or post 81 and adapted to be held by nuts 112 on opposite sides thereof, serves to engage the rear end of the long arm of the bell crank 104 at its connection with the rod or link 108, for the purpose of determining and regulating the proper move-

ment of the rack 58. Thus, without checking the movements of the diapers or other articles when they reach the discharge end of the conveyor, but merely by intercepting the light beam from the light source to the photosensitive cell and switch between the sides of the frame of the conveyor and above the endless member thereof, the counter is automatically actuated intermittently as the articles pass, to give an accurate total of the number of articles in a batch of laundry. This obviates the necessity of providing a baffle plate or board and hopper, for checking the discharge of the articles tending to permit several articles to bog together because natural gravitation of the articles was too slow when the speed of the conveyor was heightened or increased, as well as clogging of the hopper in discharging the articles from the conveyor and advancing the counter wheels or disks with the numbers thereon, to give the proper total by the stamping mechanism pressing the card against the number wheels and digits thereof, with the intermediate inking ribbon as described. When one end of the ribbon is reached, the feeding thereof may be easily reversed by shifting the rod 97 and the gears to reverse the feed of the ribbon. The securing means for the top plate 71 of the guide slot in which the card is inserted, is indicated at 113.

In view of the foregoing description taken in conjunction with the accompanying drawings it is believed that a clear understanding of the device will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. In combination, a counter including type-carrying counting wheels, an electro-magnet operable to intermittently advance said counting wheels, and a shaft operable to reset said counting wheels to zero, an inking ribbon movable across said counting wheels, means to guide a record card into position over the counting wheels and the inking ribbon, a vertically reciprocable hammer movable downwardly to press the record card against the inking ribbon and impress the inking ribbon on the counting wheels, a vertically swingable hand lever for moving said hammer downwardly, spring means for raising said lever and said hammer means operated by said hand lever for advancing the inking ribbon when said hand lever is raised and means operated by said hand lever for operating said shaft to reset the counting wheels to zero when said hand lever is raised.

2. The construction defined in claim 1, in combination with manually operable means for reversing the ribbon advancing means.

3. The construction defined in claim 1, wherein said means for operating said shaft comprises a pinion fixed thereon, a rack bar meshing with said pinion, a bellcrank lever, a link connecting one arm of said bellcrank lever to said rack bar, and a second link connecting said hand lever to the other arm of said bellcrank lever.

4. The construction defined in claim 1, wherein said means for advancing the inking ribbon comprises a feed shaft, a ratchet device for turning said feed shaft including a ratchet head having

an arm operatively connected to the hand lever, shafts carrying spools onto which the inking ribbon may be selectively wound, and manually operable means to selectively operatively connect the feed shaft to the shaft of either desired 5 spool.

LAURA BLANCHETTE DUNCAN.
